F. L. GORMLEY,
LIFTING JACK,
APPLICATION FILED FEB. 18, 1919.

1,315,928.

Patented Sept. 9, 1919.

Inventor:
Frank L. Gormley,
by Walter E. Lombard,
Atty.

UNITED STATES PATENT OFFICE.

FRANK L. GORMLEY, OF BROOKLINE, MASSACHUSETTS, ASSIGNOR TO A. O. NORTON, INC., OF BOSTON, MASSACHUSETTS, A CORPORATION OF MAINE.

LIFTING-JACK.

1,315,928.

Specification of Letters Patent

Patented Sept. 9, 1919.

Application filed February 18, 1919. Serial No. 279,457.

To all whom it may concern:

Be it known that I, FRANK L. GORMLEY, a citizen of the United States of America, and a resident of Brookline, in the county of Norfolk and Commonwealth of Massachusetts, have invented certain new and useful Improvements in Lifting-Jacks, of which the following is a specification.

This invention relates to lifting jacks and particularly to that class of lifting jacks known as screw jacks.

The object of the present invention is to provide a simple means for adjusting the bevel gears of the jack so that they will be in proper mesh at all times.

The invention consists in providing the main casing with an inclined surface with which coacts the tapered end of an adjusting member threaded to the cover plate supporting the spindle or shaft of the driving gear whereby vertical movement may be imparted to said cover plate relatively to the casing to which it is attached.

The invention consists further in the provision of a locking device for retaining the adjusting member in adjusted position.

The invention further consists in certain novel features of construction and arrangement of parts which will be readily understood by reference to the description of the drawings and to the claims hereinafter given.

For the purpose of illustrating the invention, one preferred form thereof is illustrated in the drawings, this form having been found to give satisfactory and reliable results, although it is to be understood that the various instrumentalities of which the invention consists can be variously arranged and organized, and that the invention is not limited to the precise arrangement and organization of the instrumentalities as herein shown and described, except as required by the scope of the appended claims.

Of the drawings:

Figure 1 represents a sectional elevation of a lifting jack embodying the features of the present invention.

Fig. 2 represents an elevation of the lower part of the cover plate and the adjusting and clamping members therefor.

Fig. 3 represents a sectional detail of the adjusting device and the locking mechanism therefor.

Fig. 4 represents a sectional detail of

the adjusting member and showing the serrated head therefor, and

Fig. 5 represents a section on line 5—5, on Fig. 3.

Similar characters indicate like parts throughout the several figures of the drawings.

In the drawings, 10 represents a suitable base supporting a stationary standard 11 over the outer periphery of which is fitted a movable sleeve 12, to the upper end of which is threaded a cap 13. In the upper end of the standard 11 is mounted a nut 14 to which is threaded a lifting screw 15 having splined to its upper reduced end a gear 16 with which meshes a gear 17 formed upon or secured to a revoluble shaft 18, the outer end of which is provided with a suitable operating mechanism 19 of any well-known construction.

Interposed between the upper face of the gear 16 and the inner face of the cap 13 are two annular plates 20 and 21 between which are interposed a plurality of anti-friction members 22. Between the plate 20 and the upper face of the gear 16 is a friction disk 23.

The movable sleeve 12 is provided with a rectangular chambered extension 24 in which is mounted a train of gearing which is not shown or described in detail as it forms no part of the present invention.

The chambered extension 24 is provided with a cover plate 25 having a plurality of vertical slots 26 therein through which extend the shanks of the clamping bolts 27, said shanks being threaded to the extension 24.

The cover plate 25 is provided with a bearing 28 for the shaft or spindle 18.

It is obvious that by loosening the clamp bolts 27, the cover plate may be moved vertically to bring the gears 16 and 17 in proper mesh.

One of the horizontal walls of the extension 24, preferably the lower wall, is provided with an inclined surface 29 with which coacts the tapered end 30 of an adjusting member 31. This adjusting member 31 is threaded to the cover plate 25 and when rotated therein it will be moved endwise in an obvious manner.

If the adjusting member 31 is moved inwardly into the position indicated in Fig. 3, the tapered end 30 coacting with the in-

clined surface 29 will move the cover plate upwardly relatively to the extension 24 as shown in said Fig. 3, provided the clamping bolts 27 have previously been loosened to permit this adjustment.

When the cover plate 25 has been positioned properly, the bolts 27 are clamped again to the cover plate to retain it in adjusted position.

10 If the adjusting member 31 is locked in position it is obvious any downward movement of the cover plate 25 is effectually prevented.

15 To provide a suitable locking device for said adjusting member 31, said member is provided with a cylindrical head 32 having turning wings 33 on the outer face and a plurality of V-shaped serrations 34 on its inner face.

20 Projecting inwardly from the cover plate 25 is a tubular boss 35 having a diametral slot 36 in its inner end, said slot having parallel flat sides.

25 In the tubular boss 35 is positioned a cylindrical bolt 37 with its outer wedge-shaped end 38 projecting beyond the outer face of said cover plate 25 and coacting with the V-shaped serrations 34 in the head 32 of the adjusting member 31.

30 The bolt 37 is provided with a square shank 39 extending through the slot 36 with two flat sides thereof coacting with the flat sides of the slot 36 and thereby preventing said bolt from rotating about its axis.

35 Within the tubular boss 35 and surrounding the shank 39, is a spring 40 adapted to force the bolt 37 outwardly and cause the wedge shaped end 38 to coact with the serrations 34 at all times.

40 These serrations are of such a shape that when pressure is applied to the wings 33, the adjusting member 31 may be rotated, the bolt 37 moving inwardly against the tension of the spring 40.

45 As soon as the member 31 has been adjusted, further accidental rotation thereof is prevented by the locking bolt 37.

This makes a very simple and effectual means for adjusting the cover plate 25 and bringing the gears 16—17 into proper mesh.

It is believed that the operation and many advantages of the invention will be fully understood without further description.

Having thus described my invention I 55 claim

1. In a lifting jack a casing having a lateral rectangular extension, a horizontal inner wall of which is provided with a beveled surface; a cover plate for said extension provided with vertical slots; bolts extending through said slots into said extension; and an adjusting member threaded to said cover and provided with a tapered end coacting with said inclined surface.

60 2. In a lifting jack a casing having a lat-

eral rectangular extension, a horizontal inner wall of which is provided with a beveled surface; a cover plate for said extension provided with vertical slots; bolts extending through said slots into said extension; 70 an adjusting member threaded to said cover and provided with a tapered end coacting with said inclined surface; and means for locking said member in adjusted position.

3. In a lifting jack a casing having a lateral rectangular extension, a horizontal inner wall of which is provided with a beveled surface; a cover plate for said extension provided with vertical slots; bolts extending through said slots into said extension; an adjusting member threaded to said cover and provided with a tapered end coacting with said inclined surface; a head on said adjusting member having serrations on its inner face; and a locking member co- 80 acting with said serrations.

4. In a lifting jack a casing having a lateral rectangular extension, a horizontal inner wall of which is provided with a beveled surface; a cover plate for said extension provided with vertical slots; bolts extending through said slots into said extension; an adjusting member threaded to said cover and provided with a tapered end coacting with said inclined surface; a head on said adjusting member having serrations on its inner face; and a spring pressed bolt 90 having a wedge shaped end coacting with said serrations.

5. In a lifting jack a casing having a lateral rectangular extension, a horizontal inner wall of which is provided with a beveled surface; a cover plate for said extension provided with vertical slots; bolts extending through said slots into said extension; an adjusting member threaded to said cover and provided with a tapered end coacting with said inclined surface; a head on said adjusting member having serrations on its inner face; and a spring pressed bolt 100 having a wedge shaped end coacting with said serrations; said bolt having associated therewith means for preventing its rotation.

6. In a lifting jack a casing having a lateral rectangular extension, a horizontal inner wall of which is provided with a beveled surface; a cover plate for said extension provided with vertical slots; bolts extending through said slots into said extension; an adjusting member threaded to 115 said cover and provided with a tapered end coacting with said inclined surface; a head on said adjusting member having serrations on its inner face; a spring pressed bolt having a wedge shaped end coacting with said 120 serrations and a flat sided shank; and a flat sided fixed bearing for said shank.

7. In a lifting jack a casing having a lateral rectangular extension, a horizontal inner wall of which is provided with a 130

beveled surface; a cover plate for said extension provided with vertical slots, and a tubular boss on its inner face having an axial flat sided slot in its inner end; bolts 5 extending through said slots into said extension; an adjusting member threaded to said cover and provided with a tapered end coating with said inclined surface; a head on said adjusting member having serrations 10 on its inner face; a spring pressed bolt hav-

ing a wedge shaped end coating with said serrations and a square shank extending through the slot in said tubular boss.

Signed by me at 4 Post Office Square, Boston, Mass., this 17th day of February, 15 1919.

FRANK L. GORMLEY.
